UNITED STATES PATENT OFFICE

HOWARD J. KERR, OF WESTFIELD, NEW JERSEY, ASSIGNOR TO THE BABCOCK & WILCOX COMPANY, OF BAYONNE, NEW JERSEY, A CORPORATION OF NEW JERSEY

TUBE FOR MERCURY BOILERS

Application filed June 5, 1929. Serial No. 368,538.

This invention relates to a vapor generating element of a mercury boiler and to a mercury boiler comprising a multiplicity of such elements. The vapor generating elements are connected to the lower sides of drums or headers in which a supply of liquid mercury is provided, and in which the mercury vapor from the tubes of the elements is collected after separation from the liquid. The invention will be understood from the description in connection with the accompanying drawings in which Fig. 1 is a vertical section through a mercury boiler showing the device in position; Fig. 2 is a side view of a group of the tubes; Fig. 3 is a vertical section through one of the tubes; Fig. 4 is a section on an enlarged scale along the line 4—4 of Fig. 2; Fig. 5 is a section on an enlarged scale along the line 5—5 of Fig. 2; Fig. 6 is a section on an enlarged scale along the line 6—6 of Fig. 2; Fig. 7 is a section along the line 7—7 of Fig. 5; Fig. 8 is a side view of a modified group of tubes; Fig. 9 is a vertical section showing a feed tube; Fig. 10 is a section on an enlarged scale along the line 10—10 of Fig. 9; Fig. 11 is a section on an enlarged scale along the line 11—11 of Fig. 9; Fig. 12 is a section on an enlarged scale along the line 12—12 of Fig. 8; Fig. 13 is a section along the line 13—13 of Fig. 11; and Fig. 14 is a section along the line 14—14 of Fig. 11.

In the drawings reference character 1 indicates a furnace above which the mercury boiler is located. The boiler comprises a row of horizontally disposed headers 2 placed side by side with spaces between them to permit hot products of combustion to pass through. Vapor generating tubes 3 are connected to the lower sides of the headers 2 and are contacted by the hot gases from the furnace 1.

Zigzag baffles 5 are provided between groups or rows of tubes to cause the hot gases to pass across the tubes. These baffles 5 may be suspended from spacers 6 that are located between the headers 2. A layer of heat insulating material 6' may be provided along the lower side of headers to pro-

tect the same from the intense heat of the furnace.

Connectors 7 are provided to connect groups of vapor generating tubes to the headers 2. Each connector 7 comprises an upper tubular portion and a lower expanded portion 8, the lower portion being of sufficient size to receive a number of vapor generating tubes circumferentially disposed about a center core. The connectors 7 extend through the lower walls of the headers 2 and are connected thereto in any convenient manner, as, for example, by welding, as indicated at 9.

A circular plate 10 is connected at a lower end of each connector 7, being preferably welded thereto, as indicated at 11. A number of vapor generating tubes 12 circumferentially disposed about a center core 28 have their upper ends extending through holes in the plate 10 and may be connected to this plate by welding, as shown at 13. In each tube 12 is provided a liquid displacer 14, which might advantageously have the form of a twisted flat strip as shown, to contribute towards causing the rising mixture of mercury and vapor to sweep along the inside surfaces of the tubes 12. When tubes are of a sufficiently small diameter such liquid displacers may be omitted.

The lower ends of the tubes 12 extend through the holes in a slightly dished metal plate 15 and are welded therein, as indicated at 16. A tubular extension 17 extends upwardly through a hole at the center of the plate 15.

Radial metal fins 18 (Fig. 6) may be provided between tubes 12 in contact with these tubes to act as spacers. When these fins 18 project beyond the tubes 12, as shown in Fig. 6, they contribute towards heat transmission to the tubes. These fins may be welded in place, as indicated at 18'.

An end cap 19 is provided at the lower end of each group of tubes. The circumferential edge of each cap 19 is welded to the edge of the necked fitting 15, as indicated at 20. The cap 19 is provided with a central hole or recess 21 with a conical projection 22 in the bottom thereof. Passages 100

23 extend from the central hole 21 to positions below the ends of the tubes 12.

A feed tube or liquid supply tube 24 has its upper curved end welded in an opening 25 through the connector 7 at a point near the upper side of the lower wall of the header 2. The tube 24 extends through the circular plate 10 and is welded thereto, as indicated at 26, and the lower end of the tube 24 is welded to the extension 17, as indicated at 27. The tube 24 is preferably provided with bends intermediate its ends, as indicated in Fig. 9, to provide for expansion and contraction. The space between the 15 circumferential vapor tubes 12 and the central liquid tubes 24 may be advantageously filled with a solid material 28 selected so as not to prevent compensation for expansion and contraction of the tubes, and at the 20 same time limit the heat received by the liquid tubes 24. The construction is operative and useful without such filling 28, as the circumferential vapor tubes 12 act as a shield for the liquid tubes 24.

25 In the modification shown in Figs. 8 to 14, the plate 30 at the lower end of the expanded end 8 of the connector 7 is made sufficiently thick to have a reduced upper portion 31 to extend some distance into the 30 expanded portion 8 of the connector 7. The lower end of the connector 7 is welded to the plate 30, as indicated at 32. In this modification the bundle of tubes 33 are twisted or slightly helical to provide for 35 expansion, as shown in Fig. 8, and the upper ends of the tubes 33 extend through the plate 30 and are welded in place, as indicated at 34.

The lower ends of the tubes 33 extend 40 through holes in the lower plate 35 and are welded thereto, as indicated at 36. A conically shaped cap 37 has its upper edge welded to the plate 35, as indicated at 38, and is provided with a central opening 39 into 45 which the feed tube 24 extends and is welded in place, as indicated at 40. Passages 41 extend from the central opening 39 to the lower ends of the tubes 33.

The operation is as follows:

50 Liquid mercury that is introduced into the headers 2 passes downwardly through the feed tubes 24 that are shielded from the hot gases by means of the circumferentially disposed vapor tubes 12 or 33, which may be 55 supplemented by mouldable filling mate-

rial 28. The liquid mercury passes outwardly through the passages in the cap at the lower end of each liquid tube and thence upwardly through the circumferentially disposed vapor tubes, where the mercury is converted into vapor by means of the hot gases from the furnace contacting with the tubes 12 or 33. The mixture of mercury and vapor passes into the headers 2 through the connectors 7. The vapor is taken off 70 through connectors at the upper sides of the headers 2 and the liquid mercury collects in the lower portions of the headers 2 returning to the feed tubes 24.

This invention belongs to the class of mercury boilers having dead-end tubes which project downwardly into the furnace and are heated by the hot gases. Heretofore these tubes have consisted of single tubes provided with cores to displace the liquid mercury and to provide for a high velocity of vapor when formed. By means of the present construction more surface is provided for the generation of vapor in the space occupied by one tube, and by a multiplicity of small tubes arranged in a cylindrical bundle, the necessity for cores does not exist provided the tubes are of a sufficiently small diameter. By this invention also thermal metal may be used in the construction of the tubes, which is advantageous considering the high temperatures employed and the high rates of heat transmission procurable.

I claim:

1. In a mercury boiler, a liquid supply tube, a plurality of vapor generating tubes around said supply tube, and heat insulating material between said supply tube and the other tubes and supported in place by said last named tubes.

2. In a mercury boiler, a vapor generating unit including a liquid supply tube, a plurality of vapor generating tubes around said supply tube, and fins between the tubes of said group contacting with the vapor generating tubes and means connecting said tubes at adjacent ends.

3. In a mercury boiler, a liquid supply tube, a plurality of vapor generating tubes around said supply tube, and mouldable heat insulating material between said supply tube and said vapor generating tubes and supported in place by said last named tubes.

HOWARD J. KERR.
